UNITED STATES PATENT OFFICE

BENJAMIN F. CONNER, OF HARTFORD, CONNECTICUT

DESIGN FOR A JAR OR SIMILAR RECEPTACLE

Application filed June 24, 1932. Serial No. 44,179. Term of patent 7 years.

To all whom it may concern:

Be it known that I, BENJAMIN F. CONNER, a citizen of the United States, residing at Hartford, in the county of Hartford and State of Connecticut, have invented a new, original, and ornamental Design for a Jar or Similar Receptacle, of which the following is a specification, reference being had to the accompanying drawing.

Of the drawing:

Fig. 1 is a top view of a jar or similar receptacle embodying my invention.

Fig. 2 is a side view.

In the drawing certain portions are stippled to represent contrasts in color between the said portions and the adjacent portions which are not stippled.

I claim:

The ornamental design for a jar or similar receptacle as shown and described.

BENJAMIN F. CONNER.
